UNITED STATES PATENT OFFICE

165,205

COMBINED STOCK AND DIE UNIT

Clyde E. Wright, Elyria, Ohio

Application February 1, 1951, Serial No. 14,074

Term of patent 14 years

(Cl. D54—13)

To all whom it may concern:

Be it known that I, Clyde E. Wright, a citizen of the United States, and resident of Elyria, in the county of Lorain, State of Ohio, have invented a new, original, and ornamental Design for a Combined Stock and Die Unit, of which the following is a specification, reference being had to the accompanying drawings, forming a part thereof.

Fig. 1 is a top plan view of a combined stock and die unit, showing my new design;

Fig. 2 is a side elevational view thereof; and

Fig. 3 is a bottom plan view thereof.

Fig. 4 is a sectional view along line 4—4 of Fig. 3;

Fig. 5 is a sectional view along line 5—5 of Fig. 3;

Fig. 6 is an end elevational view of the combined stock and die unit.

I claim:

The ornamental design for a combined stock and die unit, substantially as shown.

CLYDE E. WRIGHT.
